UNITED STATES PATENT OFFICE.

GIDEON SUNBACK, OF MEADVILLE, PENNSYLVANIA, ASSIGNOR TO HOOKLESS FASTENER COMPANY, A CORPORATION OF PENNSYLVANIA.

SHEET-METAL FORMING AND SETTING MACHINE.

1,331,884.

Specification of Letters Patent. Patented Feb. 24, 1920.

Application filed March 16, 1916. Serial No. 84,550.

To all whom it may concern:

Be it known that I, GIDEON SUNBACK, a subject of the King of Sweden, residing at Meadville, in the county of Crawford 5 and State of Pennsylvania, have invented certain new and useful Improvements in Sheet-Metal Forming and Setting Machines, of which the following is a full, clear, and exact specification.

10 This invention relates to a machine for forming and setting metal punchings, and has particular reference to a special form of power press with automatic blank feeding means whereby punchings are formed 15 from a strip blank and set on a carrying element.

The machine illustrated herein is intended for forming the fastener members shown in my Patent 1,219,881, dated March 20, 20, 1917, and affixing them to the corded fabric tape shown therein. The fastener members consist of separated jaws and an interlocking member having a recess on one side and a head on the other, these respective 25 recesses and heads being arranged on a pair of tapes so as to alternately interlock.

30 The machine of the present invention has for its object to form and set these fastener members on the tape with one handling of the material, and a further object of the invention is to enable the machine to automatically set these interlocking members in separated groups of a predetermined number each, so that the tape can be cut apart 35 to provide fasteners of desired length.

The present invention is not limited in its broad aspects to the production of the particular fastener members referred to, nor to the setting of such members on tapes, 40 but is of general application wherever it is desired to automatically and cheaply form large numbers of like parts, and to set them on a suitable carrier element.

45 A feature of novelty in the invention resides in the construction whereby the punching is completely separated from the blank and is then immediately replaced therein so that it can be further fed for the subsequent operations, of shaping and setting, or 50 the latter alone, by the blank feed without applying the setting tools directly to the punching. Owing to the necessity of making the fastener members as nearly alike as

possible, in order that they will lock and unlock properly when set on the tapes, it 55 is necessary to have the utmost accuracy in the shaping and setting operations subsequently to the punching out from the blank, and by causing the punching to be replaced in the blank and controlled thereby, it is possible to apply pressure to the punching through the blank so as to hold the punching firmly during the shaping operation, and then by a further side punching operation through the blank, the jaws 60 are firmly set on the carrier element or tape without leaving any tool marks upon the jaw members themselves. After the jaw members are set, the residue of the blank is fed out in one place and the carrier element having the jaw members affixed thereto is fed out in another direction. The avoidance of tool marks on the jaw members themselves is of decided advantage, since it cheapens the subsequent finishing 75 required in the finished fastener.

In carrying out the invention, various novel combinations and sub-combinations in the controlling, feeding, punching, pressing and setting mechanisms have been secured, all of which will be more fully understood in connection with the description of the accompanying drawings, wherein

Figure 1 is a side elevation of a machine;

Fig. 19 is a plan view on an enlarged scale showing the blank and the punchings in different stages of progress;

Fig. 20 is an enlarged top view showing the blank under a yielding presser plate permitting the punchings to be fed forward with the blank without disengagement;

Fig. 21 shows an additional detail of the tape feed, and

15 Fig. 22 is a timing diagram.

1 represents a metal blank, which is preferably in the form of a flat strip, and is fed into the machine from the rear toward the front. The machine is applicable to sepa-

20 rate blanks as well as to a continuous strip, but in making very small fasteners such as herein shown, which are approximately one-eighth inch long and one-sixteenth inch wide when fastened and applied to the tape,

25 it is preferable to employ a strip. Referring to Figs. 1 and 4, the blank 1 enters guide 2 and passes through feed rolls 3, 3, then through guide 9 to the die unit 10, and between the side guide plate 11 (see Figs.

30 3 and 8). The guide plates 11 are controlled by wedges 12 (see Figs. 3 and 8). The wedges 12 are operated through a slide 13 (see Figs. 3 and 4), and cam plates 14 by the punch head 15, held in the slide 16 (see

35 Figs. 9 and 10) and moved up and down through connecting rod 17 and crank 18 on the main shaft 8. The feed rolls 3, 3 are operated by ratchet 4, pawl 5 and connecting rod 6 from eccentric 7 mounted on the main

40 shaft 8 (see Figs. 1 and 2).

22 is the blanking punch which punches out the entire member and the piece 34 into die 23 (see Figs. 3 and 4). As the punch 22 draws out of the die, the plunger 24 carried by plunger holder 25 and sleeve 26, is actuated by spring 27 to press the punchings back into original place in the metal blank 1. The piece 34 (Fig. 19) lies in the blank between the jaws 35 of the punching.

50 This scrap piece 34 is pushed out of the blank 1 by punch 36 (see Fig. 4) into the hole 37 in die unit 10. The next step is to press or form the punching in its final form ready to be clamped on the tape, and this is

55 effected by punch 38 and recess 39 in die unit 10 (Figs. 4 and 5).

On the down stroke of slide 16, as the punches are nearing the blank, the cam plates 14 (see Fig. 3) draw the wedges 12

60 toward the back, pressing the guide plates 11 toward each other with the blank in between, thus holding the blank firmly in place until released by the forward movement of the wedges 12 on the up stroke of slide 16.

65 Figs. 3 and 4 show the position at the mo-

ment the clamping movement of the guide plates 11 has been effected. To allow for wear and variation in the width of the blank 1, the space between the guide plates 11 is adjustable by blocks 19 and set screw 20 (see Fig. 3).

The function of the guide plates 11 is of vital importance. At the time of punching, the two plates hold the material firmly against spreading and distortion either of 75 the punching or of the blank. This enables the subsequent operations on the punching to be controlled through the blank, and insures such perfect shape of the finished punchings and correct positioning thereof in 80 the dies, as to produce a highly uniform and symmetrical fastener member and product. When the guide plates 11 draw tight around the blank 1, they not only bring the blank into a central position over the dies, but 85 force the punchings, if they should happen to get out of place, into correct position lengthwise of the blank. The guide plates spread apart during the feed and allow an easy and free movement of the blank. It 90 also allows the interlocking or projecting end of the fastener punching to lift up out of the recess 39 (see Fig. 4) in die unit 10 after the impression of punch 38.

At this time the blank 1, after reaching 95 die unit 10 is confined between die unit 10 on the bottom and stripper plate 21 on the top (see Fig. 8).

In order to avoid reliance solely upon spring 27 to press the punching back into 100 its original place in the blank as punch 22 withdraws, a positive movement is provided. Rod 28 in addition to spring 27 exerts pressure on sleeve 26 thus forcing the punching into its place in the blank. Rod 28 is acted 105 upon through screw 29 in lever 30 (see Figs. 9 and 10) and connecting links 31, 32 from eccentric 33 on main shaft 8. Upon the return of the punching to its proper place in the blank and with the co-operation of the 110 side guides 11, top of die unit 10 and stripper plate 21, the punching can now be fed forward by the blank feed rolls 3, 3, without any danger of becoming displaced. A displacement at this time would cause much 115 trouble, because of the extreme accuracy required in the finished fastener members of such small dimensions.

The blank after return of the punching is fed forward as above stated so that the 120 scrap piece 34 can be pushed out of the blank 1 by punch 36, and then the punching is pressed into recess 39 in die unit 10 by punch 38 to form the interlocking recess and projection. At this time, it is necessary to hold the blank and punching down onto the face of the die unit 10 and also to hold it against lateral spreading by contraction of the side guides 11. The stripper 125 plate 21 partly performs this function, but 130

in addition there is provided a yielding presser or floater 40 (see Figs. 5, 6, 7, 20) which is mounted in stripper plate 21 and bears down on the jaws 35 of the punching, 5 and on the blank 1, by means of springs 41 (see Fig. 4) and plunger 42. This plunger 42 is timed and adjusted to commence pressure as soon as the forward movement of the blank stops, and can be adjusted to exert a.

10 positive pressure upon the blank and punching by contacting with a lug on punch block 15 when the punches are in their lowest position. Thus the blank and punching are firmly held in position while the trans- 15 versely elongated recess and projection are formed by the punch 38 and die recess 39.

When the blank 1, still carrying the fastener member, which is now finished and ready to be pressed on the tape, is again 20 fed forward, the floater or presser 40 yields upwardly so as to permit the projection of the fastener member to lift out of the die recess 39 so that it can be carried forward into recess 43 (Figs. 3 and 4) ready to be 25 set. To prevent the fastener member punching from lifting out of the blank 1 altogether, the lift of the yielding presser 40 is limited as shown in Fig. 7^a. Figs. 6 and 6^a show the presser 40 at its lowest position and Figs. 7 and 7^a show it at its highest position.

The finished punching is now carried forward by the next motions of the feed rolls 3, 3 until it reaches the position where the 35 jaws 35 straddle the corded edge of the tape 44 (see Fig. 19). The tape 44 is fed intermittently upward and at right angles to the blank feed through the hole and slot 45 (see Figs. 3 and 4) in die unit 10. In 40 this position the jaws 35 are clamped around the corded edge of the tape by side tools 46 (see Figs. 3 and 19) which simultaneously press toward each other on the outside of the blank 1, while the formed 45 jaw member is being held between the top of the die unit 10 and the resilient presser 40 (see Figs. 3 and 4). Each of the side tools 46, which set the jaw members on the carrier element, tape, or stringer, is held 50 in and moved through the slide 47 which is connected at 48 by lever 49, rock shaft 50, arm 51, and link 52 to punch block 15 (see Fig. 2). When the clamping movement is completed, the tape feeds up 55 and lifts the jaw member clamped to its corded edge, out of the residue of the blank 1, the tape and attached jaw member passing through slot 53 in floater 40 (see Fig. 5). There now remains of the blank 1 only 60 the two edges, which are fed through the tubes 54 (see Figs. 3 and 4) and cut into small pieces by knives 55 connected to the actuating heads 48 of the side tools, the pieces falling down through chute 56.

65 In order to prevent slipping of the feed,

the blank 1 is maintained clean and dry while engaged by the feed rolls 3, 3, and the necessary lubrication of the blank is done after it has passed the feed. This is accomplished by an ordinary oil pump 57 70 (see Fig. 1) which drips the lubricant down in funnel 58 mounted centrally over the blank 1. Soap and water is preferably used as a lubricant, because it does not leave a stain on a fabric tape.

75 The supply of tape is wound on spool 59 (Fig. 1) and passes from there through passageway 60 under the bed of the machine and up through tension 61 (see Figs. 15 and 17), also passing through the hole 80 and slot 45 (see Fig. 3) in the die unit 10. The tape then passes between the sides of the blank 1 where the interlocking members are clamped around the corded edge, and then leads through slot 62 in the punch holder and then around disk 63 (see Figs. 15 and 17). Then the stringer or tape leads to spool 64 (see Figs. 1 and 2) on which it is wound up by belt 65 driven from the main shaft.

90 The movements of the tape are controlled by the disk 63 on shaft 66. Shaft 66 is driven by ratchet 67 (see Figs. 17, 11 and 12) through pawl 68, bell crank 69 and pitman 70 connected to crank plate 71 by 95 radially adjustable crank pin 97 mounted on the main shaft 8. The grip of disk 63 on the tape is produced by the sliding shoe 72 (see Figs. 15, 16 and 17) which presses the tape against a knurled or roughened periphery of disk 63. The grip is also obtained by pressure of the tape on the knurled disk 63 produced by the tension 61, whose function is to hold the tape taut between the die unit 10 and the tape feed 100 control at disk 63. Disk 63 has a groove 73 for the jaw members on the stringer, which groove serves as a leader and prevents the tape from lateral displacement while passing around the disk 63. Sliding 105 shoe 72 is pressed against the disk 63 by springs 74, whose tension is released by lever 75 in the position shown in Fig. 16. The springs 74 are made of such length as to permit the shoe 72 to be lifted out of 110 contact with the disk 63, (see Fig. 16) to facilitate the threading or removal of the tape between the disk and the shoe.

115 Fig. 21 shows the position of the shoe 72 relatively to the disk 63. By reason of the shoe being pointed at the tape entering end, producing friction between the slanting edge 76 and the tape sliding under shoe 72, the tape tends to follow the direction of edge 76, or to work itself over to the side. 120 Thus the corded edge of the tape, with or without metal, is sliding with considerable pressure against the edges 98 of the shoe 72, and the edges of the groove in disk 63, thus placing the grip on the tape close to 125 130

the corded edge. The corded tape is made so that the corded edge is shorter than the free edge, the latter being wavy, so that the corded edge thus takes practically all of the strain of the feed. It is therefore necessary in order to secure even and uniform spacing of the jaw members, that the tape be gripped in feeding close to the corded edge. The clamping of the jaw members on the tape produces some elongation of the corded edge of the tape.

The slanting edge 76 has the additional function of preventing puckering or doubling up of the tape in front of shoe 72. This is because the point of shoe 72 slides over the tape near the corded edge, at a point where the tape is not only taut but is held firmly by its attachment to the cord, so that as the tape glides in under the shoe, the edge 76 flattens out any wrinkles in the same manner as the divergent edges of a flat iron would do.

Instead of the shoe 72, a slightly conical idler roller having its high edge engaging the corded edge of the tape can be used to press the tape against the knurled periphery of disk 63. This idler roller being controlled by springs 74.

The tape tension 61 (see Figs. 15 and 18) comprises two tension plates 77 having grooves for the cord which provide guiding means as well as friction surface. These plates are mounted loosely on the ends of jaws 61 which are pivotally connected at 103 and normally pressed apart by spring 107 mounted between screw bushings 79 which can be turned so as to vary the spring pressure at plates 77. The pressure on the jaws is transmitted through the screw 78 disposed at about the center of the plates 77, so that the plates can rock slightly on the ends of the screws and adjust themselves to irregularities in the tape without affecting the friction. In order to prevent puckering, the plates 77 at the lower or entering end are tapered or cut away so as to smooth out a puckered or wrinkled tape in the same manner as above described with respect to edge 76 of shoe 72. The tape tension is not fastened to the machine, but is held in place by the friction of the tape which in its upward motion holds the tension against the lower side of die unit 10. 80 (see Fig. 17) is a brake holding the shaft 66 and tape roll 63 against movement except through ratchet 67.

The throw of pawl 68 (Figs. 11 and 12) which drives the tape feeding shaft 66 through ratchet 67 is made longer than is necessary to feed the required length of tape for proper spacing. To regulate the spacing, (see Fig. 11) a shield 81 is provided which prevents the pawl 68 from dropping on the teeth of ratchet 67 until the desired throw of shaft 66 has been provided. The spring 82 pushes the pawl into engagement

with the teeth as soon as the pawl clears the shield 81. The shield 81 is adjustable around shaft 66 so as to control the number of teeth pawl 68 will feed.

The present machine is designed to fix a predetermined number of equally spaced jaw members on a given length of tape, and then to feed a blank length of tape to enable the fasteners to be cut apart to receive the additional sliding member not shown herein and also end stop devices. The pawl 68 automatically feeds the excess length of tape required for this purpose, through a second pawl 83 (see Figs. 13 and 14) pivoted on pin 84 and held against pin 85 by spring 86. Pawl 83 is mounted on the friction ratchet 87, mounted between ratchet 67 and shield 81 with a bearing fit on shaft 66. The secondary pawl 83 thus extends over teeth of ratchet 67, and the friction ratchet 87 is held against accidental rotary movement by brake 88 (see Figs. 13 and 14) fastened to shield 81 by screw 89. As the secondary pawl 83 is carried around on the friction ratchet 87, it reaches the position where pawl 68 at the rear end of its stroke rides over it. At the beginning of the forward movement pawl 68 then catches the secondary pawl 83. The spring 86 (see Fig. 13) yields to the pressure of pawl 68, allowing the secondary pawl 83 to swing until its forward edge engages the teeth of ratchet 67. The swinging movement being arrested, continued pressure of pawl 68 carries with it the secondary pawl 83, the two ratchets 87 and 67, 100 the shaft 66 and the tape. The ratchet 87 is moved by ring 98 (see Fig. 13) through rolls 90 and spring 91. Arm 92 which operates ring 98 is operated by the spring 93 and the pin 94 in clamp 95 attached to the connecting rod 6, and operated by eccentric 7. The stroke of arm 92 is adjustable by the micrometer head 96 in bracket 97 (see Fig. 14) attached to the frame of the machine. The adjustment ranges from a maximum length equal to the throw of connecting rod 6 to a very small minimum. Thus the secondary pawl 83, carried around by the friction ratchet 87, is made to complete a single revolution during a predetermined 115 number of operations of the machine according to the setting of micrometer 96. When the secondary pawl 83 is effective, it will be seen that a long throw will be given the tape feed, equal to the full stroke of 120 pawl 68.

If not much variation in the lengths of fasteners is required, the friction ratchet with secondary pawl 83 can be dispensed with. In this case the ratchet 67 is provided 125 with a high tooth 99 (see Fig. 11) which will project up above the surface of shield 81 so as to be caught by pawl 82 during each revolution of ratchet 67. By changing the throw of pawl 68, the length of the metal part of 130

the fastener can be varied to a limited extent without changing the over-all length including the tape ends. To materially change the length of the fastener the number of teeth in the ratchet 67 can be varied, and also the diameter of feed disk 63.

5 The fastener members as affixed to the tape may require further finishing to remove burs, but this can be done after the members 10 are attached to the tape much more cheaply than by additional finishing operations in the machine before the members are pressed on the tape.

15 While the machine has been described with reference to the making of the members from a strip, the novel principles of the invention are applicable to the feeding of separate pieces, and it will be obvious that in applying these broad features of the invention to 20 other machines some of the parts herein described may be modified or omitted entirely without departing from the invention, and all such modifications will be within the scope of the appended claims.

25 Having thus described my invention, I declare that what I claim as new and desire to secure by Letters Patent, is:—

1. The combination of means for cutting a flat member having separated compressible jaws at one end, means for forming a recess and head on the other end, means for feeding the jaw end astride a carrier, means for feeding the carrier, and means for pressing the jaws together on the carrier.

30 2. The combination of means for cutting a flat member having separated compressible jaws at one end, means for forming a recess and head on the other end, means for feeding the jaw member adjacent a carrier, and means for pressing the jaws together on the carrier through interposed means preventing tool marking of the jaw member.

35 3. The combination with means for punching out a blank, of means for replacing the punching in the blank, means for feeding the blank and punching forward, means for shaping the punching, means for clamping the punching to a carrier, and means for separately feeding out the blank.

40 4. The combination with blank feeding means of complete punching out means, means for replacing the punching in original position in the blank to permit it to be further fed by said blank feeding means, means for feeding a carrier, and means for setting the punching on the carrier by pressure through the blank after the punching has been replaced in the blank and fed 45 away from said punching out means.

45 5. The combination with blank feeding means, of means for punching out and replacing in the blank a jaw member, means for shaping said jaw member, means for feeding a carrier member between the jaws

of said shaped member while held in the blank, and means acting on said blank for setting said jaw member on said carrier member.

6. The combination with blank feeding 70 means, of means for punching out and replacing in the blank a jaw member, means for shaping said jaw member, means for feeding a carrier between the jaws of said shaped member while held in the blank, 75 means acting on said blank for setting said jaw member on said carrier member, and means for feeding the carrier member and the attached jaw member away from the blank.

7. The combination with means for feeding a blank, of means for forming and replacing a punching in the blank, means for shaping the punching and simultaneously applying pressure to opposite edges of the 85 blank, and means for feeding out the punching and the blank.

8. The combination with blank feeding means, of punching means, means for compressing the blank edgewise, means for replacing the punching in the blank, and means for shaping the punching and co-operating means for holding it and the blank against lateral distortion.

9. The combination with blank feeding 95 means, of punching means, means for compressing the blank edgewise, means for replacing the punching in the blank, means for shaping the punching and co-operating means for holding it and the blank against 10 lateral distortion, and means for feeding a stringer and setting the shaped punching thereon.

10. The combination with blank feeding means, of punching means, means for replacing the punching in the blank, means for feeding a carrier element transversely of the blank and the replaced punching, and means for setting the punching on said carrier element.

11. The combination with blank feeding means, of means for punching out a member to be set on a carrier element, means for feeding a carrier element to the point of attachment, and setting means acting through 115 an interposed waste part of said blank.

12. The combination with a blank and blank feeding means, of means for punching out a member from said blank in condition to be compressed, a compressing tool, 120 said feeding means interposing a portion of the blank between the tool and the punched out member to be compressed.

13. The combination with means for feeding a member to a compressing tool, and a 125 compressing tool, of means for guiding a protective piece between the tool and the member to be compressed.

14. The combination with a blank and blank feeding means, of a die unit and a 130

- spaced stripper plate, interposed movable side guides, means for punching said blank and means for actuating the guides toward each other to compress the blank at the moment of punching. 5
15. The combination with a blank and intermittent blank feeding means, of a die unit and a spaced stripper plate, interposed movable side guides, means for punching said blank and means for actuating the guides toward each other to compress the blank at the moment of punching and for spreading the guides while the feed is effective. 10
16. The combination with intermittent blank feeding means, of punching means, and movable means for clamping the blank against sidewise spreading while being punched and releasing the blank during the blank feeding. 15
17. The combination with intermittent blank feeding means, of compressing means, means for punching out and replacing the punching in the blank, means for holding said punching under transverse compression while said punching and replacing takes place, means for relieving the compression for the next feed, means for forming a projection on the replaced punching, and yielding means permitting passage of the projection out of its die without displacing it from its blank, upon further feed of the blank. 20
18. The combination with blank feeding means, of means for punching out a member from the blank, die means for forming a projection on said member simultaneously with means holding the member under side and face compression, and means for relieving both of said compressions to permit said blank feeding means to feed said member out of the projection forming die. 25
19. The combination with blank feeding means, of a punch for cutting out a member having jaws, means for replacing the punching in the blank and for feeding stepwise forward, a second punch for ejecting a waste piece adjacent the jaws of said member, means for forming a projection in said member, and means for feeding the punching out of the machine. 30
20. The combination with means for cutting a member having jaws, means for forming a socket in said member, of means for feeding a carrier element transversely between said jaws, and side punches for automatically pressing the jaws toward each other on the edge of said element. 35
21. The combination with means for cutting a member having jaws, means for forming a socket in said member, of means for feeding a tape between said jaws, and means for pressing the jaws on the edge of the tape. 40
22. The combination with means for cutting a member having jaws, means for forming a socket in said member, of means for feeding a continuous carrier element between said jaws, means for pressing said jaw members on said carrier element, and means for varying the feed of said continuous carrier element to vary the spacing of said jaw members. 45
23. The combination with means for cutting a member having jaws and means for forming a socket in said member, of means for feeding a tape between said jaws, means for controlling the tape tension, and means for automatically pressing the jaws on the edge of said tape. 50
24. The combination with means for feeding attachable jaw and socket elements, clamping means for holding the said elements and setting means for the jaws, of means for feeding a corded tape to receive said jaws on the corded portion of said tape, and tension means engaging the corded portion of said tape. 55
25. The combination with means for punching out a blank, of means for replacing the punching in the blank, means for feeding the blank and punching forward, means for clamping the punching to a carrier, and means for separating the blank and the attached punchings. 60
26. The combination with intermittent blank feeding means, of complete punching out means, means for replacing the punching in original position, and movable means for clamping the blank against sidewise spreading while said replacement of the punching takes place. 65
27. The combination with blank feeding means, of punch and die mechanism for cutting out a jaw member and a waste piece adjacent the jaws of said member, means for replacing the punchings in the blank for the purpose of feeding stepwise forward and means for pushing out said waste piece. 70
28. The combination with blank feeding means, of means for punching out pieces, comprising a piece having jaws and a waste metal piece, means for replacing the pieces in original position in the blank for further feeding by said blank feeding means, means for separating the jaw piece from the blank and means for removing the waste piece. 75
29. The combination with blank feeding means, of a punch and die mechanism for cutting out two pieces, means for replacing the pieces in the blank, means for feeding the blank and pieces, means for forming one of said pieces while held in the blank, and means for pushing out the other piece. 80
30. The combination with means for feeding a sheet metal blank, of means for punching out of said blank and replacing therein a punching having separated jaws at its forward end, and means for attaching said jaws to a carrier element. 85
31. The combination with means for feed- 85

- ing a sheet metal blank, of means for punching out of said blank and replacing therein a punching having separated jaws at its forward end, and means for transversely compressing said jaws around a carrier element. 32. The combination with means for feeding a sheet metal blank, of means for punching out of said blank and replacing therein a punching having separated jaws at its forward end in a common plane, and means moving parallel to said plane for compressing said jaws toward each other around a carrier element. 33. The combination with means for forming a socket and a projection adjacent the end of a member having jaws, of means for feeding a carrier element between said jaws, and means for automatically pressing the jaws on said element. 34. The combination with means for feeding a member having jaws at its advancing end, of means for intermittently feeding the edge of a carrier element transversely and between said jaws, and means for setting the jaws on the edge of said element. 35. The combination with means for feeding a socket member having jaws at its advancing end, of means for intermittently feeding a tape transversely between said jaws, and means for setting the jaws on said tape. 36. The combination with means for affixing a member to a strip, of means for feeding the strip at one rate to space the members, and means periodically varying the strip feed to group the spaced members. 37. The combination with means for forming and affixing a member to a strip, of means for feeding the strip at one rate to space the members, and means periodically varying the strip feed to group the spaced members. 38. The combination with means for affixing members to a strip, of means for feeding the strip, and means for varying the strip feed to vary the spacing between the members. 39. The combination with means for affixing groups of members to a strip, of means for varying the spacing between members of a group by varying the feed of the strip. 40. The combination with means for affixing groups of members to a strip, and strip feeding means, of means for feeding an increased length of strip between groups, and means for regulating the number of members in a group. 41. The combination with means for affixing groups of members to a strip, of means for feeding an increased length of strip between groups, and means for regulating the spacing of the members in a group. 42. The combination with means for feeding a strip and means for affixing fastening members on the edge thereof, of actuating means for effecting normal spacing of said members, and additional means for effecting an increased strip feed after a predetermined number of members are affixed. 43. The combination with means for successively affixing jaw members to a corded tape, means for feeding the corded tape between the jaws, means acting on the corded part of the tape to carry the feeding strain, and tension means also acting on the corded part of the tape. 44. The combination with means for feeding a fabric strip step by step, of means for feeding jaw members to and compressing same on the edge of said strip, tension means for the strip, and a fine adjustment for controlling the strip feed for maintaining accuracy of spacing of said jaw members. In testimony whereof I affix my signature, in presence of two witnesses.

GIDEON SUNDBACK.

Witnesses:

NOEL POUX,
ALGER F. RUSSELL.

DISCLAIMER

1,331,884.—*Gideon Sundback, Meadville, Pa. SHEET-METAL FORMING AND SETTING MACHINE.* Patent dated February 24, 1920. Disclaimer filed January 30, 1933, by the assignee, *Hookless Fastener Company*.

Therefore disclaims:

(a) From the scope of the claim numbered 34, any combination except one in which the member having jaws at its advancing end is a slide fastener member of the character described in Sundback patent No. 1,219,881, and which has means for automatically supplying such members to the feeding means.

(b) The claim numbered 38 in toto.
[Official Gazette February 21, 1933.]

DISCLAIMER

1,331,884.—*Gideon Sundback, Meadville, Pa. SHEET-METAL FORMING AND SETTING MACHINE.* Patent dated February 24, 1920. Disclaimer filed January 17, 1934, by the assignee, *Hookless Fastener Company*.

Hereby enters this disclaimer to that part of said specification which is in the following words, to wit:

“This invention relates to a machine for forming and setting metal punchings, and has particular reference to a special form of power press with automatic blank feeding means whereby punchings are formed from a strip blank and set on a carrying element.” (p. 1, lines 10 to 16.)

“The present invention is not limited in its broad aspects to the production of the particular fastener members referred to, nor to the setting of such members on tapes, but is of general application wherever it is desired to automatically and cheaply form large numbers of like parts, and to set them on a suitable carrier element.” (p. 1, lines 36 to 43.)

And your petitioner further disclaims from the scope of each of claims 1 to 33, inclusive, 35, 36, 37, and 39 to 44 inclusive, any combination except one for forming and affixing to a tape carrier, slide fastener members such as are described in the sentence beginning at line 21 of page 1 of the specification and reading as follows:

“The fastener members consist of separated jaws and an interlocking member having a recess on one side and a head on the other, these respective recesses and heads being arranged on a pair of tapes so as to alternately interlock.”
